STORAGE HOUSING FOR AN ELECTRIC TOOTHBRUSH

Donald A. De Varco, Cincinnati, Ohio, and Douglas G. Long, Lombard, Ill., assignor to Sunbeam Corporation, Chicago, Ill.

Filed Jan. 3, 1972, Ser. No. 215,279

Term of patent 14 years

Int. Cl. D3—02

U.S. Cl. D4—16

FIG. 1 is a perspective view of the storage housing for an electric toothbrush;

FIG. 2 is an enlarged side elevational view thereof;

FIG. 3 is an enlarged top elevational view thereof;

FIG. 4 is a front perspective view with the storage case in open position with broken lines to illustrate the electric toothbrush power handle and toothbrushes which are included to show the environment and form no part of the claimed design; and

FIG. 5 is an enlarged sectional view taken along line 5—5 of FIG. 1.

We claim:

The ornamental design for a storage housing for an electric toothbrush, as shown and described.
